METHOD FOR CONTROLLING YARN

Filed Dec. 11, 1947

UNITED STATES PATENT OFFICE

2,532,467

METHOD FOR CONTROLLING YARN

Eugene St. Pierre, Pawtucket, R. I., assignor to
 Hemphill Company, Central Falls, R. I., a corporation of Massachusetts

Application December 11, 1947, Serial No. 791,051

1 Claim. (Cl. 66—146)

1

This invention relates to a new and useful improvement in a method and device for controlling yarn in its passage from its cone or from other sources to the device by which it is used such as the needles of a knitting machine. It was devised for use with a circular, independent needle, hosiery knitting machine of the Banner type and the description will be based upon such a use. However, it is equally useful with other types of knitting machines and also with winding and other machines where the same problem is encountered. Certain yarns, particularly nylon, present special problems to the knitter. One is its tendency to untwist which apparently originates in the general vicinity of the needles and extends back through the guides and tensions to the cone. When knitting is discontinued, the yarn unwinds a little from the cone creating slack. When this occurs, the yarn tends to twist upon itself to form outstanding pigtails which when knitting is resumed may straighten out or concentrate into knots. Broken yarn, defective fabric, broken needles and other difficulties result from such knotting. It is a characteristic which has caused great annoyance to users of certain yarns of which nylon is a conspicuous example and which, as far as is known, has been eliminated only by this invention.

One form of the invention is shown in the drawing of which:

Fig. 1 is a side elevation of such parts of a Banner knitting machine as are required for an understanding of the invention;

Fig. 2 is a rear elevation of the same parts;

Fig. 3 is a view illustrating the characteristic kinking of nylon which this invention prevents;

Fig. 4 shows a modified form of the invention; and

Fig. 5 shows a second modification.

As is well known, a knitting machine is provided with one or more sources of yarn, generally a cone, from which the yarn is run through suitable guides and tensions to the yarn levers and needles. As shown in Fig. 3, yarn 1, assumed to be nylon, originates at the cone 2 and passes through eyelet 3 and, generally, additional eyelets, not shown, as well as one or more tensioning devices on its way to the yarn levers and needles.

While knitting is going on, the yarn runs continuously from the cone and is under some tension throughout its length so that no difficulties with its travel are encountered. However, when knitting is stopped, a certain amount of slack appears adjacent the cone and may extend to the far side of one or more of the yarn guides where-

2

upon the yarn is almost certain to twist upon itself into pigtails such as those shown at 4 and 5 in Fig. 3 which may or may not disappear when knitting is resumed. If they do not, knitting and mechanical troubles are certain to result.

5 The cause of this pigtailing of the yarn appears to be the untwisting of the yarn itself beginning adjacent the needle end of its travel which is reflected all the way back to the cone.

10 When slack appears anywhere, pigtailing is likely to occur particularly if the length of yarn between adjacent guides or a guide and the cone is of any great length. At times it is practically impossible to knit nylon yarn for this reason unless the machine is kept in continuous operation.

15 This difficulty has been completely solved by the simple but wholly effective method and device of this invention. The form shown in Fig. 1 consists essentially of a small spool or pulley 6 adapted to rotate with great freedom upon a pin 7 affixed to a bracket 8 which is mounted upon a suitable part, such as the spider 9, of the machine more or less midway of the travel of the yarn between the cone and the needles. The yarn 1 after passing through one or more guides such as 10 and 11 is given a turn around pulley 6 and is then led to the needles through the usual guides and tensions. While knitting is going on, pulley 6 is caused to rotate by the pull upon the yarn produced by the needles. When knitting is stopped, the pulley stops. Any tendency to overrun may be prevented by a tension 12 on the cone side of the pulley. This tension may serve as the or one of the regular tensions by which the knitting is regulated.

20 35 The pigtailing of the yarn heretofore described and which has been such a serious problem is wholly eliminated by pulley 6 used in this way. In effect, the start of an artificial pigtail is produced by the loop of yarn around pulley 6 which is prevented from twisting upon itself to form a pigtail by the pulley. Also the bending of the yarn around the pulley stops its internal untwisting. Consequently, the yarn remaining between the pulley and the cone is effectively insulated from the causes which would normally produce pigtailing since these lie on the other side of pulley 6 and cannot proceed beyond that pulley. As a result, nylon and other difficult yarns 40 45 50 can be used as easily as any of the many other yarns with which this troublesome characteristic is not encountered.

In Fig. 4 a modification is shown in which the yarn is given a partial turn instead of a full turn around a pulley 13 which corresponds to pulley

85

6. In this instance, it will be noted that the yarn reverses its direction so that the suggestion of a loop, such as that shown at 4' in Fig. 3 which is characteristic of pigtailing, is clearly suggested. To be effective, the yarn should be in contact with the pulley for a considerable length of its circumference. Otherwise, the effectiveness of the device is progressively impaired. In other words, the yarn about the pulley must have what is definitely recognizable as the beginning of a complete loop as distinguished from mere band but the exact minimum requirement depends upon so many features that it can be determined only by trial.

In the form of the invention illustrated by Fig. 5, it will be noted that there are two pulleys 14 and 15, each corresponding to pulley 13 and that the yarn is passed around one side of one pulley and around the other side of the other pulley. While the directions of the ends of the yarn are divergent, the suggestion of a definite loop, such as that shown in Fig. 4 is preserved. In this instance, there are two such loops. In both the modified forms, as in the original form, the pulley or pulleys act as before with the result that pigtailing tendency is eliminated from the remaining yarn.

If greater resistance to the travel of the yarn is not objectionable a pin or other non-rotating element may replace the pulley and, of course, the term "pulley" includes any form of freely rotating element.

In the following claim the words "loop" and "looped" are to be understood to include not only the complete loop described in connection with the form of the invention of Fig. 1 but also partial loops or incomplete loops, such as those shown in Figs. 4 and 5 or, in other words, any loop or bend in the yarn around an element which is sufficient to eliminate the pigtailing tendency de-

scribed. The degree of bend or loop in the yarn required for the purpose of this invention will vary with the kind, size and twist of the yarn and the mechanical arrangement of the machine and, consequently, cannot be more exactly specified.

I claim:

A method of controlling a length of twisted nylon yarn running from a source of supply to 10 a point where it is used progressively, such as to a knitting needle, under conditions causing an alteration in the twist of said yarn and a consequent tendency to pigtail if slack occurs adjacent said source of supply, which includes the steps 15 of drawing said yarn from the source of supply under no tension other than that resulting from the withdrawing of said yarn to a tensioning device and thereafter forming a loop in said yarn and maintaining said loop in a single plane to 20 prohibit transmission of alterations in yarn twist and consequent tendency to pigtail in the length of yarn between said source of supply and said tensioning device.
